G. PURVIS.
SOOT EJECTOR.
APPLICATION FILED AUG. 12, 1918.

1,305,565.

Patented June 3, 1919.

UNITED STATES PATENT OFFICE.

GEORGE PURVIS, OF DETROIT, MICHIGAN.

SOOT-EJECTOR.

1,305,565.

Specification of Letters Patent. Patented June 3, 1919.

Application filed August 12, 1918. Serial No. 249,424.

To all whom it may concern:

Be it known that I, GEORGE PURVIS, a citizen of the United States of America, residing at Detroit, in the county of Wayne 5 and State of Michigan, have invented certain new and useful Improvements in Soot-Ejectors, of which the following is a specification, reference being had therein to the accompanying drawings.

10 In my pending application filed June 7, 1918, Serial No. 234,798 there is disclosed an ash ejector especially designed for flue boilers of the marine type, for removing fine ashes and soot from smoke flues and smoke 15 boxes, particularly the latter. In this pending application, the soot ejector may be considered as of the oscillatory type in contradistinction to the subject matter of this application, which is directed to soot and ash 20 removing means that may be considered reciprocatory, as such movement is imparted to the device to thoroughly cleanse the bottom of a smoke box.

The object of the present invention is to 25 provide soot and ash removing means applicable to either end of a horizontal flue marine boiler, preferably at the forward end of the boiler so that a fireman or attendant of a boiler, from time to time and without 30 a cessation in the operation of the boiler, may use the apparatus to remove soot and such other matter that may accumulate in the smoke box or usual chamber at the rear end of the boiler.

35 The manner in which I attain the above and other objects will hereinafter appear, and reference will now be had to the drawing, wherein—

Figure 1 is a longitudinal sectional view 40 of a conventional form of marine boiler provided with an ash and soot removing apparatus in accordance with this invention;

Fig. 2 is a front elevation of the same;

Fig. 3 is a perspective view of a soot collecting head, and

Fig. 4 is a longitudinal sectional view of 45 a portion of a boiler showing a portion of the apparatus operable from the rear end of the boiler.

50 As illustrating an installation of the ash and soot removing apparatus, I have shown a conventional form of horizontal flue marine boiler as consisting of a combustion chamber 1 having a door 2, an ash pit 3 having a door 4, a bridge wall 5 assisting in

supporting grates 6, and a smoke box 7 communicating with flues 8 and a stack flue 9.

Extending through the front wall 10 of the combustion chamber 1 at one side of the ash pit door 4 is a reciprocatory pipe 11 which has the rear end thereof extending through the bridge wall 5 into the smoke box 7, and the forward or outer end of the pipe 11 rests on a bracket 12 adjacent the doorway of the ash pit 3.

65 The inner or rear end of the reciprocatory pipe 11 is angular or provided with a lateral branch 13 connected to a nipple 14 of a hollow sector shaped collecting head 15 that normally rests upon the bottom of the smoke 70 box 7. As the bottom wall of the smoke box 7 is semi-cylindrical, the lower edges of the sector shaped head 15 conforms to the wall of the smoke box, and the lower edges of said head are scalloped, notched or suitably recessed, as at 16, so that with the head resting on the bottom of the smoke box there 75 will be sufficient apertures for ashes and soot to be drawn into said head.

80 The scalloped or notched lower edges of the head 15 also serve two other purposes, namely, that of providing a plurality of projections which will scrape and remove any incrustations on the bottom of the smoke box, and prevent a complete vacuum in the 85 hollow head 15 which would retard a reciprocal movement of the same. As the head 15 provides two converging walls terminating at the nipple 14, the ashes or soot within the head will gain impetus when approaching the nipple and may be expeditiously removed through the pipe 11 without any danger of said pipe becoming clogged.

90 On the outer or forward end of the reciprocatory pipe 11 is an elbow 17 having suitable handles 18 and a suitable valve 19 the former permitting of the pipe 11 being manually reciprocated and the latter permitting of said pipe being shut off relative to its 95 source of suction.

100 As shown in Fig. 2, the marine type of boiler includes two combustion chambers and consequently two smoke boxes, but irrespective of the number of boilers, a single suction or exhaust pump 20 is provided for 105 removing the ashes and soot from the boilers. The pump 20 is of a conventional form adapted to be driven by a motor 21 and said pump has an exhaust pipe 22 to the stack or stacks of the boilers or to a suitable col- 110

lecting receptacle. As fine ashes and soot are in demand by fertilizer and chemical manufacturers, the exhaust pipe 22 may lead to collecting bins or receptacles so that the 5 ashes and soot may be saved instead of being discharged to the atmosphere.

The exhaust pump 20 has a pipe and branches 23 extending to the boiler and connected by hose or other flexible connections 10 24 to the valves 19, said valves permitting of the soot removing units being separately operated. With the pump 20 in operation and one of the valves being open, it 15 is only necessary for the fireman or attendant of the boiler to grip the handles 18 and reciprocate the pipe 11, said pipe causing the collecting head 15 to move back and forth on the bottom of the smoke box 7 and collect all the ashes and soot therein. By 20 removing the ashes and soot, from time to time, there is less liability of the soot accumulating in the flues 8 or the bottom of the stack flue 9, consequently a better draft is obtained through the smoke box and the 25 efficiency of the boiler materially increased. As shown in Fig. 4, the rear walls 25 of the boiler may be provided with a sleeve or fitting 26 through which extends an exhaust pipe 27 having the end thereof provided 30 with an ash and soot collecting head 28, similar to the head 15. It is therefore possible to install the apparatus at the rear end of the boiler, as well as the forward end thereof.

35 What I claim is:—

1. The combination of a smoke box, a reciprocatory sector shaped soot collecting head having notched walls adapted to scrape walls of said smoke box, and means connected to said head adapted for removing soot therefrom and facilitate reciprocating said head.

2. In a boiler having ash pits and smoke boxes, a soot collecting head in each box 40 centrally thereof and adapted to mechan-

ically agitate walls of the box, an exhaust pump, and means extending through each ash pit at one side thereof connected to a side wall of each head and said pump so that the contents of said heads may be removed by said pump. 50

3. In a boiler having an ash pit and smoke box, a soot collecting head reciprocable on the bottom of said box, an exhaust pump, and a pipe extending through said 55 ash pit connecting said head to said pump so that the contents of said head may be removed by said pump and said head reciprocated in said smoke box.

4. In a boiler having a smoke box, a reciprocatory exhaust pipe extending therein, and an ash and soot collecting head on the inner end of said pipe and normally resting on the bottom of said smoke box, said head having walls and being sector shaped with 60 an open end conforming in shape to the bottom wall of said smoke box and the walls of said head being recessed to establish communication between said smoke box and said head. 65

5. The combination with a boiler having smoke boxes, ash pits and bridge walls, of reciprocatory pipes extending through the front wall of the boiler, and through said bridge wall at the sides of the ash pits and 70 into the smoke boxes, collecting heads on said pipes in said smoke boxes and extending toward the bottom of each box, an exhaust pump in communication with said pipes, means adapted for independently controlling the communication between said pump and each said pipe, and means carried by each pipe adapted to facilitate manually reciprocating said pipe. 75

In testimony whereof I affix my signature 80 in the presence of two witnesses.

GEORGE PURVIS.
